(74) *Attorney, Agent, or Firm* — Jose Cherson Weissbrot

(57) **CLAIM**

The ornamental design for a spray mop, as shown and described.

DESCRIPTION

FIG. 1 is a first perspective view of a spray mop showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2; and,

FIG. 11 is an enlarged view of the selected portion 11 in FIG. 6.

The dash-dash broken lines depict portions of the spray mop that form no part of the claimed design. The long dash-short dash broken lines depict enlargement indications and form no part of the claimed design.

1 Claim, 11 Drawing Sheets
